UNITED STATES PATENT OFFICE

SAMUEL BERGSTEIN, OF CINCINNATI, OHIO

MACHINE AND PROCESS FOR MAKING PAPER BOXES OR THE LIKE

Application filed April 15, 1929, Serial No. 355,039. Renewed March 7, 1932.

The invention relates to improvements in paper box making machines, being a modification of the machine and process of manufacturing set forth in my copending application for Letters Patent of the United States, Serial No. 353,128, filed April 6, 1929, and a further development of the machine and process of manufacturing set forth in Letters Patents Nos. 1,461,966, July 17, 1923, 10 1,461,967, July 17, 1927, and 1,528,753, March 10, 1925.

The type of boxes generally adapted to be produced on the improved machine consists of rectangular shapes formed from box blanks cut and scored before the blanks are run on the machine for forming the boxes in knocked down form by progressive foldings and joining the folded portions together adhesively.

20 The general objects attained in the invention consist in the provision in the improved machine for producing a box of a common type, and also of special types, at relatively lower production cost and of improved construction, the improvement relating more especially to the uniformity of folding and gluing of the boxes.

A feature of the improved machine consists in novel means for folding front and rear 30 glue flaps of the box blanks on diagonal score lines, as the blanks are moved progressively on the machine, through the operating sequence of folding and gluing the blanks for effecting the structure of the box, the machine 35 being adaptable for producing a wide range in sizes of boxes of the different types, the boxes being delivered from the machine knocked down.

40 The improvements are herein set forth as applied to a common type of machine for producing knocked down boxes of the general character which the improved machine is adaptable for producing. The various novel structural features comprised in the invention make it possible to produce this type of box on the improved machine with increased output and lowered production cost.

In the accompanying drawings, which 50 serve for illustrating the invention in one form:

Fig. 1 is a plan view of the portion of a box making machine embodying the invention;

Fig. 2 is an enlarged detail sectional view on line 2—2 of Fig. 1;

Fig. 3 is a detail sectional view on line 3—3 of Fig. 1;

Fig. 4 is a sectional view on line 4—4 of Fig. 1;

Fig. 5 is a sectional view on line 5—5 of Figs. 1—4;

Fig. 6 is a sectional view on line 6—6 of Figs. 1—4;

Fig. 7 is a detail view of the delivery mechanism;

Fig. 8 is a view of a box blank;

Figs. 9—10 are views illustrating progressive foldings of the box blank.

The machine as here shown and described consists of a frame structure 10. The usual angularly adjustable table 11 for supporting a stack of box blanks 12 is supported on the frame structure at the front end of the machine, the arrangement being best shown in Fig. 2.

The box blanks are fed to the machine from table 11 by a friction roll 13 on shaft 14 coacting with a feed roll 15 on shaft 16. The feed rolls deliver the carton to carrier belts 17—18, the lower one 18 of which operates in an annular recess in the roll 15 for presenting the outer face of the belt flush with the peripheries of the rolls. The belts are spaced one from the other slightly in the plane of movement of the boxes for engaging the box blanks frictionally therebetween and moving the blanks through the first folding operation. Opposite guards 19 supported on a shaft 20 and extended downward to near the periphery of the lower feed roll and thence rearward on the machine serve for preventing the portions of the box blanks extended laterally on the opposite sides of the upper feed roll and the carrier belts from flaring upward, the lower feed roll and a series of carrier rolls 23 being of the required length for supporting the full length or width, as the case may be, of the box blanks on their under side as the blanks are moved on the machine.

90
95
100

The upper carrier belt 17 traverses rolls 21 in clockwise direction and the lower carrier belt 18 traverses rolls 15—22 over rolls 23 in counter-clockwise direction, the belts 8 running parallel one with the other in the plane of movement of the box blanks.

A common form of box blanks for boxes adapted to be produced on the machine is illustrated in Fig. 8, the blank being cut and 10 scored for holding and provided with the usual side flaps —a and end flaps b—c which are scored diagonally on score lines —e for effecting folding of the flaps parallel to the adjacent edges of the blanks. As the 15 blanks pass from the feed rollers and are moved along lengthwise by the carrier belts the outer edges of the side flaps —a, which are substantially wider than flaps —c are engaged by opposite fixed folders 24, supported by members 25 and brackets 27, which 20 act to fold the side flaps flat over the upper face of the blanks. For effecting positive action on the side flaps by folders 24, the front ends 26 of the folders are extended 25 downward into the plane of movement of the box blanks. The front and rear end flaps —c, being narrower than the side flaps, move 30 within the forward ends of the folders, out of engagement therewith, and under the folders toward the rear converging ends thereof, flaps —c being thus presented unfolded, or flat, for receiving an application 35 of glue in the operation which immediately follows.

38 The adhesive applying mechanism is of a common type and is shown conventionally only for illustrating the successive steps of forming the boxes. As shown, liquid glue is supplied from a container of any well known 40 form (not shown) by intermediate rollers 28 to the gluing rollers 29, supported on shaft 30, which contact with the box blanks and apply glue to the end flaps —c.

45 The operating mechanism for the portion of the machine described consists of a drive shaft 31 geared to shaft 30 as indicated at 32—33, and operably connected to shaft 16 of the lower feed roll by a variable friction drive 34—35, feed roll shafts 14—16 being 50 geared together as indicated at 36. The friction drive is adjustable for regulating the speed of the feed rollers by a hand mechanism 37 which serves for moving shaft 16 axially for adjusting the driven disc 35 relative to the driving disc 34. Any suitable 55 means may be employed for effecting the axial movement of shaft 16 when the member 37 is manipulated.

Upon folding of the side flaps —a of the 60 box blanks, as shown in Fig. 9, the end flaps —c extend laterally beyond the folded flaps. Flaps —a being within the planes of the glue rolls 29, glue is applied only to flaps —c, as there are no intervening portions of 65 the box blanks between the front and rear

flaps —c, the peripheries of the glue rolls may be unbroken, or continuous, and no timing between the feed rolls and the glue rolls is required.

Coating with glue rolls 29 is a pressure 70 roll 38 on shaft 39. Carrier belts 41 and 41—a, a roll 42, shown in broken detail in Fig. 2, and a belt 43 operable over a roll 44 on shaft 45 comprise the second unit of carriers for the box blanks, roll 42 being driven from shaft 30 by gear 40. A third roll (not shown) deflects the belt upwardly in an arrangement similar to the upper carrier belt 17 shown in Fig. 2. As the glue coated 75 and partially folded blanks are moved along by the second carriers, the folded side flaps —a move under opposite guards 46 and are held by the guards in their folded relation. The front end flaps —c are engaged by opposite fixed folders 47 and are turned upward 80 to vertical position. A fixed folder 48, spaced from the plane of movement of the carrier belts acts on front flaps —c as the blanks are advanced beyond guards 46 for folding the flaps on diagonal score lines —e over 85 and parallel with the folded side flaps —a.

Rear end flaps —c are also turned to vertical position by folders 47, but being foldable inverse to the direction of movement of the blanks, the flaps are deflected outward by 90 folders 48 into continued engagement with folders 47 and are then acted on by opposite rotatable folders 49 which act to fold the rear flaps —c on diagonal score lines —e over and 95 parallel with flaps —a as the blanks pass between the rotatable folders, final folding of front and rear flaps —c into engagement with flaps —a being effected by opposite belts 50 operable over pulleys 51—52 which are 100 arranged angularly to the plane of movement of the blanks and in close proximity thereto for completing the folds. From the folder belts 50 the completely folded blanks, or 105 boxes in knocked down form, are moved into engagement with the usual pressure mechanism 53—54 for completing sealing of the glued portions of the blanks and delivering the blanks from the machine.

110 The rotatable folders 49 may be operably connected in any suitable manner. As here shown in Figs. 1—4 the folders are driven by an independent motor 55, drive shaft 56, gears 57, and vertical shafts 58 upon which the folders are supported, the operation of the folders being at relatively higher speed 115 than the movement of the box blanks, timing of the folders to the movement of the blanks is unnecessary. Belts 50 are also operated through the driving connection 55—58 and pulleys 51.

120 The successive folding operations of the box blanks are illustrated in Fig. 9—10.

An important feature of the machine consists in sequence of the folding operations in either form of folding, illustrated in Figs. 125

9-10, and in the arrangement of the feeding, gluing and folding mechanism, which does not require timing of one mechanism with another for effecting the operations of the 5 several mechanisms on the box blanks or for bringing the folded portions of the blanks into exact registration one with another.

It will be observed that the folding of front and rear flaps —c, in the operation of 10 the machine herein set forth, and in the machine set forth in my aforesaid copending application for patent, is inverse one flap to the other, and both parallel to the plane of movement of the box blanks. This feature permits of relatively high speed production and 15 large output and is, accordingly, an important factor in producing boxes of this character by improved automatic machinery and a new process of forming and sealing paper 20 boxes.

I claim as my invention:

1. A machine for making paper boxes of blanks having front and rear end flaps and side flaps intermediate the end flaps, as the 25 blanks are moved on said machine, including means for moving said blanks on said machine without pause for forming the boxes, means for folding over said intermediate side flaps, means along the plane of movement of 30 the blanks for folding said end flaps diagonally over said side flaps for effecting adhesion between said end and side flaps.

2. A machine for making paper boxes of blanks having front and rear flaps and side 35 flaps intermediate the end flaps and extended laterally beyond the end flaps, as the blanks are moved on said machine, including means for moving said blanks on said machine without pause for forming the boxes, means along 40 the plane of movement of the blanks for engaging said laterally extended portions of the side flaps and for folding the same over the upper face of said blanks, means for applying adhesive to said front and rear end 45 flaps, and means for folding said end flaps diagonally over said side flaps for effecting adhesion between said end and side flaps.

3. A machine for making paper boxes of blanks having front and rear end flaps and 50 side flaps intermediate the end flaps, as the blanks are moved on said machine, including means for moving said blanks on said machine without pause for forming the boxes, means along the plane of movement of the 55 box blanks for folding said side flaps out of the plane of said end flaps, means in the plane of said end flaps for applying adhesive thereto, and means for folding said end flaps over said side flaps for effecting adhesion between 60 said end and side flaps.

4. A machine for making paper boxes of blanks having front and rear end flaps and side flaps intermediate the end flaps, as the 65 blanks are moved on said machine, including means for moving said blanks on said ma-

chine without pause for forming the boxes, means along the plane of movement of the blanks for folding said side flaps over said blanks, means for applying adhesive to said front and rear end flaps, and means for folding 70 said front end flaps and thereafter said rear end flaps over said side flaps for effecting adhesive joints between said end and side flaps.

5. A machine for making paper boxes of 75 blanks having front and rear end flaps and side flaps intermediate the end flaps, as the blanks are moved on said machine, including means for moving said blanks on said machine without pause for forming the boxes, means along the plane of movement of the blanks for folding said side flaps over said blanks, means for applying adhesive to said front and rear end flaps, means fixed along 80 the plane of movement of the box blanks for folding said front and rear end flaps upward, and operable means for further folding said end flaps for effecting adhesion between 85 said side and end flaps.

6. A machine for making paper boxes of 90 blanks having front and rear end flaps and side flaps intermediate the end flaps, as the blanks are moved on said machine, including means for moving said blanks on said machine without pause for forming the boxes, means along the plane of movement of the blanks for folding said side flaps over said blanks, means for applying adhesive to said front and rear end flaps, means fixed along 95 the plane of movement of the box blanks for folding said front and rear end flaps upward, operable means for further folding said end flaps, and means for pressing said folded flaps flat upon the box blanks for effecting 100 adhesion between said folded portions. 105

7. A machine for making paper boxes of 110 blanks having front and rear end flaps and side flaps intermediate the end flaps, as the blanks are moved on said machine, including means for moving said blanks on said machine without pause for forming the boxes, means along the plane of movement of said blanks for folding certain of said flaps and means for applying adhesive to said unfolded flaps, means for folding the unfolded flaps 115 relative to said folded flaps, and means for further folding the last folded flaps for effecting adhesion between said side and end flaps.

8. A machine for making paper boxes of 120 blanks having front and rear end flaps and side flaps intermediate the end flaps, as the blanks are moved on said machine, including means for moving said blanks on said machine without pause for forming the boxes, means fixed along the plane of movement of the blanks for folding said side flaps over 125 said blanks, means for applying adhesive to said end flaps, means for partially folding said end flaps, means operable for further 130

- folding said end flaps, and means operable for pressing the end flaps into engagement with said side flaps for effecting adhesion therebetween.
9. A machine for making paper boxes including means for moving paper blanks, fixed blank folding means, operable means for applying adhesive to the blanks, fixed blank folding means and operable blank folding means, coordinated one with another in the order named along the plane of movement of the blanks on said machine for forming said boxes.
10. A machine for making paper boxes from blanks including means operable for applying adhesive to said blanks, means operable for folding and sealing said blanks, and means operable for moving said blanks without pause and without operable timing of the blanks to said gluing means and thence to said folding and sealing means for producing said boxes.
11. A machine for making paper boxes from blanks including means operable for applying adhesive to portions of said blanks, means for partially folding said blanks, means operable constantly in the plane of the blanks for further folding and sealing said folded portions of the blanks, and means operable for moving said blanks without pause and without operable timing of the blanks to said gluing means and thence to said folding and sealing means for producing said boxes.
12. A machine for making paper boxes from blanks including means operable for applying adhesive to portions of said blanks, means for partially folding portions of said blanks above the normal plane of the blanks, means operable constantly in the plane of said folded portions of the blanks for further folding and sealing said portions, and means operable for moving said blanks without pause and without operable timing of the blanks to said adhesive applying means and thence to said folding and sealing means for producing said boxes.
13. A machine for making paper boxes from blanks having front and rear end flaps and side flaps intermediate the end flaps, including opposite means fixed along the plane of movement of the box blanks for folding said side flaps over the blanks, opposite means operable in the plane of movement of the box blanks for applying adhesive to said end flaps, opposite means fixed along the plane of movement of the blanks for partially folding said end flaps, opposite means operable in the plane of movement of said blanks for further folding said end flaps, and opposite means operable in the plane of the box blanks for pressing said end flaps into engagement with said side flaps for effecting adhesion therebetween.
14. A process for making paper boxes consisting in moving box blanks without pause for forming the boxes, in folding portions of the blanks, in applying adhesive to unfolded portions of the blanks, in partially folding said adhesive coated portions, and in further folding said adhesive coated portions for effecting adhesion between said portions and the first folded portions.
15. A process for making paper boxes consisting in arrangement means for folding portions of box blanks, means for applying adhesive to other portions of said blanks, means for folding and sealing said adhesive coated portions relative to said first folded portions, and means for moving the box blanks progressively, without pause and without timed relation into operable relation with said folding, gluing and further folding and sealing means for effecting formation and delivery of said boxes from said machine knocked down.
16. A process for forming flat folded paper boxes from blanks having side flaps for forming the sides of the boxes and end flaps having diagonally articulated attachment flaps for attachment to said side flaps which consists in continuously moving the blanks, folding in the side flaps during their continuous movement, applying adhesive to the attachment flaps during their continuous movement and finally folding over the attachment flaps into adhesive contact with said side flaps while said continuous movement continues.
- In testimony whereof, I affix my signature.
